ABSTRACT OF THE DISCLOSURE

A wire descaler for mechanically breaking the scale on wire by a system of scale-breaker rollers arranged to flex and bend the wire along each circumferential section of each axial length thereof and subsequently abrade the wire while advancing it longitudinally through a rotatably driven elongated container having therein an abrasive material rotatably driven and held in close contact with the wire abrading the wire circumferentially and longitudinally.

The present invention relates generally to removal of scale and rust from wire and more particularly a method and apparatus for mechanically breaking the scale on wire and removing it and rust by abrasion.

Metallic wire whether heat treated or otherwise generally oxidizes and has scale formed thereon. This scale is generally removed before the wire is processed into finished products. The scale is removed by pickling, chemically or mechanically.

Mechanical descaling and cleaning of wire has generally been by brushing the wire which is a relatively ineffective method of cleaning wire. The brushes tend to wear and are not effective throughout each circumferential section of the wire. Mechanical wire cleaning apparatus is also known using steel wool packing in a steel box through which the rod or wire is advanced longitudinally. Other mechanical apparatus includes the use of steel balls in a tilted box. The box is rocked longitudinally of the wire to effect a scrubbing action between the balls and the wire or rod which results in mechanical deformation of the wire and sometimes breaks it. Each of the known mechanical techniques and apparatus have a major disadvantage in that they are substantially ineffective to completely clean the wire and will in most cases result in a reduction of the diameter of the wire being cleaned and descaled. The wire is reduced in diameter because it must generally be subjected to excessive tension forces or due to the mechanical working of the parts on the wire.

It is a principal object of the present invention to provide a wire descaler for mechanically breaking the scale on wire and abrading the wire.

A feature of the invention is the provision of a rotator assembly comprising a rotatably driven elongated container in which is contained in operation an abrasive material for abrading the wire circumferentially and longitudinally while it is advanced longitudinally through the container and the abrasive material. The container is provided with a system of baffles effective to rotate and retain the abrasive material in close contact with the wire and bearing thereon circumferentially to carry out effective abrading circumferentially and longitudinally of the wires.

Another feature of the invention is the provision of a mechanical scale-breaker system comprising a plurality of breaker rollers disposed in respective planes bending and flexing the wire so that each angular or circumferential section of each length is mechanically bent thereby positively breaking the scale over the entire surface of the wire before it is subjected to abrading.

The apparatus in accordance with the invention provides a simple construction which carries out tumbling of abrasive material for cleaning the wire. The known tum-

2

bling techniques have the material or parts being cleaned tumbled and in the apparatus in accordance with the invention the abrasive material is tumbled while permitting continuous movement longitudinally of the wire without tumbling thereof. The apparatus includes no breakable parts and there is no possibility of overloading the unit or motor as may happen when the parts themselves are being tumbled. Moreover, the apparatus does not over-tension the wire or mechanically damage it nor reduce its diameter.

Other features and advantages of the mechanical wire descaler in accordance with the present invention will be better understood as described in the following specification and appended claims in conjunction with the following drawing in which:

FIG. 1 is a plan view of a mechanical wire descaler in accordance with the invention;

FIG. 2 is a side elevation view of a wire descaler in FIG. 1; and

FIG. 3 is a section view taken along section line 3—3 of FIG. 1.

The term wire as hereinafter used includes rigid rods and bars and bendable rods. The term wire is not limited to any particular type of metallic material.

As illustrated in FIG. 1 a wire 1 is taken from a delivery reel 2 and advanced longitudinally through a scale-breaker system of rollers 3 and through a rotator assembly 4 having a base as shown and is taken up by a rotatably driven take-up reel 5. It will be understood that the scale-breaker 3, mounted on the rotator assembly 4, can be used in conjunction with the rotator assembly 4 or independently thereof and likewise the rotator assembly 4 can be used without the need of the system 3, for example in descaling of rigid rods, however, a preferable embodiment makes use of both components to maximize scale and rust removal from the wire being processed. Moreover, when rigid rods are being scaled the reels 2, 5 are not needed.

The wire 1 is advanced longitudinally through a guide 9 and over a first breaker roller 10 where it is subjected to bending and passes over a second breaker roller 12 disposed in a second plane normal to a first plane in which the first roller is disposed. The wire passes over the second roller and moves on to a third breaker roller 14 disposed in a third plane normal to the second plane and parallel to the first plane and then moves downwardly to a fourth breaker roller 16 which is in a fourth plane parallel to the second plane in which the second roller is disposed and, of course, normal to the first mentioned plane. The wire is then advanced upwardly over the periphery of a fifth roller 18 in the first plane.

The axes of rotation of the five breaker rollers are spaced in three dimensions and it can be seen that the wire is bent over a part of the periphery or circumference of the individual rollers in such a manner that each circumferential or angular portion of the wire is subjected to bending along the entire axial length of the wire. The relative relationship of the breaker rollers insures that each part of the angular circumferential areas along each length of the wires are subjected to flexing and bending that is positively effective to break scale thereon.

After passing through the roller system the wire is guided through or over a guide 30 through a tubular drive shaft 32 supported on bearings 33, 34 having sheaves 36 fixed thereto and driven by belts 38 from motor pulleys driven by a motor 39. The drive shaft 32 is fixed to a container 40 driven rotatably and supported on the bearing 34 and another bearing 42 supporting a rotary hollow shaft 43 coaxial with the tubular shaft 32. The rod or wire 1 extends axially into and through this hollow con-

tainer and passes outwardly thereof through the hollow shaft 43 under a guide 45 where it is taken up by the take-up reel 5, which is driven by means not shown.

The container 40 is an elongated container rotatably driven at about forty to eighty-seven revolutions per minute. Within the container is contained abrasive material 47. The container is approximately three-quarters filled with the abrasive material which may be, for example, aluminum oxide. The abrasive material is made of large granules which are sufficiently large so as not to be measurable by mesh size.

The container has a polygonal cross-section and is illustrated as having an octagon configuration. In the example illustrated the octagon is about twelve inches across and has an axial length in the order of about five feet for processing wire or rod $\frac{7}{8}$ to $\frac{1}{4}$ inch in diameter. The interior of the container is provided with a plurality of elongated baffles 50 disposed intermediate corners of the polygon formed by flat sides 52 of the container. The baffles are normal to their respective sides of the container and extend inwardly toward the axis of rotation of the container in the order of about one inch and divide the container into elongated spaces 54 which are diametrically opposed.

The baffles are effective to rotate and maintain the abrasive material in direct bearing contact with the wire 1 extending axially therethrough so that abrading takes place circumferentially and longitudinally of the wire as it is continuously moved longitudinally through the container and abrasive material. The speed of the rotation of the drum or container must be in the range heretofore described in order to insure that there is sufficient abrading to clean the scale. If the speed is too slow the surface rust is not eliminated. This rust is generally found underneath the scale.

The container is provided with flat sides 52 one of which is formed as a full length door 55 provided with a full length hinge 56 and locked by wing nuts 57 along the side of the drum. The sides 52 of the drum are provided with a plurality of holes or openings 60 spaced axially on the container to allow scale to fall out of the container. These holes may be, for example, $\frac{5}{16}$ in diameter.

Those skilled in the art will recognize that the wire or rod is descaled and the rust, which is under the scale, removed therefrom by a new method in which the wire is abraded without tumbling of the wire itself and preliminarily positive breaking of the scale and partial descaling takes place by bending and flexing the wire in each angular extent thereof along the full length of the wire being processed.

While a preferred embodiment of the invention has been illustrated and described it will be understood that many changes can be made within the true spirit and scope of the invention.

What I claim and desire to be secured by Letters Patent is:

1. A mechanical wire descaler for mechanically breaking scale on wire and descaling thereof comprising, a rotator assembly comprising an elongated container driven

5 rotatably in operation for containing in operation an abrasive material for scrubbing wire circumferentially and longitudinally to remove scale therefrom, means for guiding wire to be descaled longitudinally of the interior of said container and through said abrasive material while said container is rotatably driven in operation circumferentially of said wire and said wire advanced longitudinally through said container and through abrasive material therein, said container being at least half-filled with abrasive material, and means projecting inwardly in said container effective in operation to continuously retain said abrasive material close to and frictionally bearing circumferentially of and longitudinally of said wire during rotation of said container in operation and longitudinal advancement of said wire therethrough, thereby to effect a scrubbing action on said wire effective to remove scale therefrom.

10 2. A mechanical descaler according to claim 1, including a system of scale-breaker rollers comprising five rollers over which said wire travels and having axes disposed spaced in three dimensions, a first pair of said rollers disposed in a common plane, a second pair of rollers disposed in parallel planes normal to said common plane, and a fifth roller disposed in a plane normal to the last-mentioned plane and parallel to said common plane.

15 3. A mechanical wire descaler according to claim 1, in which said means in said container to retain said abrasive material close to and bearing circumferentially of and longitudinally of said wire comprise a plurality of baffles 20 extending inwardly into said container and longitudinally thereof defining spaces therebetween diametrically opposite to each other and effective to move said abrasive material from upper spaces to lower spaces as said container is rotatably driven and retain said abrasive material from 25 moving outwardly away from said wire longitudinally of said container.

30 4. A mechanical wire descaler according to claim 3, in which said container defines a polygon in cross section, and in which a baffle is disposed intermediate each pair 35 of corners of said polygon.

35 5. A mechanical wire descaler according to claim 4, in which said container comprises flat sides, and in which said baffles are normal to a respective one of said flat sides.
